UNITED STATES PATENT OFFICE.

JOHN E. MITCHELL AND WALTER G. E. ROLAFF, OF ST. LOUIS, MISSOURI, ASSIGNEES TO
WALTER G. E. ROLAFF, OF ST. LOUIS, MISSOURI.

REFRIGERATING MACHINE.

Application filed January 8, 1922. Serial No. 527,301.

To all whom it may concern:

Be it known that we, JOHN E. MITCHELL and WALTER G. E. ROLAFF, citizens of the United States, residing in the city of St. Louis and State of Missouri, have invented new and useful Improvements in Refrigerating Machines, of which the following is a specification.

This invention relates to refrigerating machines and has for one of its objects to provide a machine of this character in which the lubrication of the working parts is automatically effected in the operation of the machine, and at the same time, the body of lubricant employed operates to prevent any leakage of gas from the machine.

Other objects of the invention relate to the provision of a refrigerating machine in which the high pressure or condensing chamber is superimposed upon the low pressure or evaporating chamber, the compressors being located in the low pressure chamber and operated by a shaft passing from the outside through the low pressure chamber and having bearings in corresponding walls of the two chambers; to provide a reciprocating refrigerating machine which shall be dynamically and mechanically balanced; to provide a reciprocating refrigerating machine in which the cylinders of the compressors are insertable from the outside into the low pressure chamber and are substantially entirely surrounded by the cool gas of said chamber; to provide automatic lubricating means involving the maintenance of a substantially uniform height of a lubricant in the high pressure and low pressure chambers, the provision of means for controllably discharging lubricant from the high pressure chamber by the pressure of gas therein, its automatic application to the moving parts of the machine and passage to the low pressure chamber, and the continuous return of the lubricant to the high pressure chamber effected by the operation of the compressors located in the low pressure chamber; to provide a novel construction of refrigerating machine of the reciprocating type in which a vertically disposed drive shaft enters the machine through a stuffing box in the bottom of the low pressure chamber and in which chamber a body of lubricant is constantly maintained and has free access to said stuffing box whereby the latter is sealed against the escape of gas.

The above objects of the invention are attained by means of the machine shown in the accompanying drawing which will be found to be characterized by the following salient features:

A high pressure chamber superimposed upon the low pressure chamber; a vertically disposed shaft driven at its lower end by a motor, entering the machine through a stuffing box in the bottom of the low pressure chamber and passing into the high pressure chamber, the port through the stuffing box constituting the only opening containing a moving part through which gas might escape and which opening is sealed against such escape of gas by means of a body of lubricant maintained in the bottom of the low pressure chamber and having free access to said stuffing box; a body of lubricant maintained in the high pressure chamber; a means of communication between the high pressure chamber and the compressing mechanism in the low pressure chamber; a valve member on the upper end of the vertical shaft operating alternately to open and close said communication whereby the pressure of gas in the high pressure chamber will cause a certain amount of the lubricant to be forced through the means of communication to the low pressure chamber to fall upon said moving parts which act as distributing agents to convey the lubricant to all parts of the machine, after which the lubricant flows to the bottom of the low pressure chamber; a plurality of compressors, preferably two, located opposite each other in the low pressure chamber with means for operating the pistons thereof synchronously in the same operative direction to effect simultaneous similar actions by each piston; and means for insuring a uniform and equal return of the lubricant from the low pressure chamber to the high pressure chamber by each of the compressors.

In the drawing—

Figure 1 represents a vertical sectional view of a machine embodying our invention; and

Figure 2 is a detached sectional view on the line 2—2 of Figure 1.

Referring now to the drawing, the numeral 1 indicates a support for the machine, which is in the form of a cylindrical casing surrounding a motor 2. As shown, the

cylindrical support 1 is provided with an interior annular flange 3 and the motor is provided with a corresponding outwardly projecting annular flange 4 which rests upon the flange 3 to which it is secured by means of bolts 5. Projecting vertically upward from the motor 2 is the main drive shaft 6 which in view of the arrangement of compressors hereafter to be described, is provided with a fly-wheel 7. Mounted on the cylindrical support 1 is the refrigerating machine which will now be described.

The numeral 8 indicates a circular wall surrounding a chamber 9, the upper part of the support 1 being shouldered to receive the lower edge of the wall, as shown. The chamber 9 is provided with a removable bottom 10 which has shouldered connection with an annular flange 11 projecting inward from the wall 8 and is bolted in fluid and gas tight relation to said flange by means of the bolts 12. The bottom 10 is provided on its upper side with a bearing 13 for the shaft 6 and on its under side supports a stuffing box 14 of conventional construction, through which said shaft extends. The bearing 13 is provided with a series of apertures 15 for permitting lubricant "x" supplied to the chamber 9, to pass directly to the packing 16 of the stuffing box for the purpose of sealing the opening surrounding the shaft against escape of gas from the chamber 9. This chamber constitutes the low pressure chamber of the machine and, as stated above, it is characteristic of the invention that the compressors of the machine are located in this chamber, and this construction and arrangement will now be described.

The wall 8 is provided at a plurality of points, preferably two located directly opposite each other, with circular openings 17 through which are inserted from the outside, the cylinders 18 of two compressors, these cylinders being of less diameter than that of the opening 17 to provide a space the thickness of the wall 8 at this point surrounding the cylinders. Each of the cylinders is provided with ports 19 communicating with the space referred to and, therefore, with the interior of the chamber 9. Each of the cylinders is provided on its outer end with a head 20 and each of these heads is provided with an annular flange 21 which has shouldered connection with the wall 8 surrounding the aperture 17 and is secured thereto in fluid and gas tight relation by bolts 22. Each of the heads 20 also provides a valve chamber 23 which is closed on the outer side by a plate 24. A cap 25 is screwed on the outer end of each of the heads 20 and securely closes the end of the head 20 and seals it against the escape of any gas which may pass by the plate 24. Projecting inwardly from the plate 24 is a lug 26, this lug and the plate 24 with which it is integral, being

apertured to slidably receive a stem 27 projecting inwardly from a circular plate 28 which is in the nature of a floating head and acts as a valve to control the opening of the inner end of the cylinder 18. A coil spring 29 extending between the plates 24 and floating heads 28 operates to hold the latter in yielding contact with the inner end of the cylinder 18. Mounted in each cylinder 18 is a piston 30 which in its outward throw, as shown in the drawing, reaches a point substantially flush with the outer end of the cylinder. Mounted in each of the pistons 30 is a wrist pin 31 with which is pivotally connected the outer end of a piston rod 32. Each of the pistons 32 is provided on its outer end with a ring 34 which surrounds and is supported on a cam disk 35 mounted on the shaft 6. The respective cam disks 35 are mounted in superposed relation and oppositely disposed so that the pistons 30 move in unison inwardly and outwardly. By this arrangement the dynamic and mechanical forces are equalized or balanced and a smooth running machine is insured. In order to assist in carrying the pistons through the compression zones, we prefer to utilize the inertia of the fly-wheel 7 to further insure the smooth and even running of the machine. To insure the adequate oiling of the cam disks and rings, the following construction and arrangement is provided:

The upper eccentric ring 35 has mounted on its upper side an inverted conical cup 36, open at its upper end and surrounding the shaft 6, which receives lubricant supplied from the high pressure chamber in a manner to be later described. The upper cam disk 35 is provided with a duct 37 leading from the outer surface of the disk on the inside of the cup 36 to the periphery of the disk. This upper disk is also provided with a vertically disposed duct 38 the upper end of which is within the cup 36 and the lower end of which communicates with a duct 39 in the lower disk 35 which latter duct extends through to the periphery of its disk. It may be briefly noted at this point that lubricant from the cup 36 will pass through the ducts 37, 38 and 39 and will be thereby supplied to lubricate the bearings of the cam disks 35 and rings 34.

As previously mentioned, a characteristic of the invention is the fact that the high pressure or condensing chamber is superimposed upon the low pressure chamber. This arrangement and the construction and operation of parts associated therewith will now be described.

The high pressure chamber 40 is formed by a hollow circular head 41 and a circular wall 42 projecting upward from a circular web or partition 43 which is at once the top of the chamber 9 and the bottom of the chamber 40. The lower edge of the wall 130

of the head 41 has shouldered relation with the upper edge of the wall 42, and corresponding flanges 44 on the respective walls afford means for bolting the head in position by means of a plurality of bolts 45, the connection, of course, being fluid- and gas-tight. Each of the valve chambers 23 previously referred to, is provided at its bottom with a port 46 from each of which a pipe 47 leads to and communicates with the high pressure chamber 40. Located within the high pressure chamber 40 is a condensing coil 48 which has inlet and outlet pipes 49 and 50 respectively, communicating with a suitable source of cold water circulation. The numeral 51 indicates the outlet pipe for conducting the liquid refrigerant from the chamber 40 which pipe is provided on the interior of the chamber 20 with a goose-neck 52, the mouth of which is adapted to be submerged in the liquid refrigerant as the latter rises in the chamber so that the refrigerant may escape under the pressure in the chamber through this pipe. After passing through the room, container, or other zone of refrigeration, the refrigerant in the form of a gas is conducted into the low pressure chamber 9 through a pipe 51^a, which, of course, is a continuation of the pipe 51 and which enters the chamber 9 through the bottom 10 thereof. Within the chamber 9 the outlet end of the pipe 51^a, indicated by 52, is located above the surface of the body of lubricant "x" always maintained in said chamber.

Referring again to the chamber 40 the heavy hatched lines "x" indicate a body of lubricant while the lighter hatched lines "y" indicate the liquid refrigerant which rests upon the body of the lubricant. The manner of circulating the lubricant will now be described.

Centrally of the partition 43 there is provided a bearing 53 for the shaft 6 and through which said shaft extends into the chamber 40. On its upper end within this chamber the shaft has secured, as by being screwed thereon as shown, a circular valve 54 the seat for which is afforded by the upper side of the bearing 53, which for this purpose is provided with a circular projection 55, at least the lower side of which is always submerged in the body of lubricant "x". At a given point near its outer edge the circular projection 55 is provided with a vertically disposed aperture 56. The bearing 53 is provided with a parallel aperture or duct 57 which extends from the top of the bearing through the same and communicates at the lower end of the bearing with the chamber 9 immediately over the open end of the cup 36. The valve 54 normally closes the aperture 56 but it is provided on its under side with a cut-away portion or

recess 58, which when it passes over the top of the aperture 56, which position is shown in the drawing, establishes communication through the ports 56 and 57 between the high pressure chamber 40 and the low pressure chamber 9, so that the pressure of gas in the former chamber bearing upon the lubricant, will force the same up through the port 56, whence it passes through the recess 58 under the valve and into the duct 57, dropping into the cup 36. This action occurs in each complete revolution of the valve 54. It should be stated that the valve 54 is in the form of a ring valve which affords between its inner circumference and the disk, a chamber 60 into which the lubricant passes from the recess 58 of the valve before escaping through the duct 57 into the cup 36. The circular projection 55 of the bearing is reduced and screwthreaded in its upper portion to receive a screw cap 61 which at once shields the valve 54 and bearing 53 against access of the liquid refrigerant in the chamber 40 and also forms on top of the bearing a chamber to retain the lubricant forced through the aperture 56 in the manner previously described. The manner of returning the lubricant from the low pressure to the high pressure chamber is as follows:

The numerals 62 indicate two pipes communicating with the cylinders 18 slightly in advance of the ports 19 therein and leading therefrom to a point adjacent the bearing 13 where they are connected by a T-coupling 63, the leg of the coupling having its open end located near the surface of the body of lubricant "x" in the low pressure chamber, forming as it were, an inverted cup. With each inward stroke of the pistons lubricant will be drawn by suction into the T-coupling 63 and thence through the pipes 62 into each cylinder, and with each outward stroke, it will be forced, along with the refrigerant, through ports 46 and pipes 47 into the high pressure chamber.

In operation a container of a liquid refrigerant, preferably methyl chloride, is connected in any suitable way to the low pressure side of the system and the motor 2 placed in operation and on each inward stroke of the pistons 30, the gaseous methyl chloride will be drawn into the cylinders 18 through the ports 19 and on each outward stroke of the pistons the gas will be compressed between the end of the piston and the head, and in the latter portion of the outward stroke the head 28 will yield to permit the escape of the compressed gas which passes into the chamber 23 and thence through the port 46 and pipe 47 to the high pressure chamber 40 whence it is condensed by contact with the cool pipes of coil 48 and converted into a liquid form. A float valve

51^b in pipe 51 operates automatically to hold the gas in the high pressure chamber until it is condensed into a liquid and until the liquid rises above the mouth of the goose 5 neck 52 in said chamber, after which the valve is raised by and releases the liquid. A body of liquid refrigerant, indicated by "y" in the drawing, will thus be constantly formed and maintained in the chamber 40, 10 and which will rest upon the body of lubricant "x" previously supplied to this chamber. The liquid refrigerant will escape through the goose neck 52 and pass by way of the pipe 51 through the refrigerating system 15 and thence return as a gas through the pipe 51^a to be discharged through the outlet 52 of said pipe into the low pressure chamber 9 whence it will enter the compressors and be returned to the high pressure chamber, as 20 previously described. With each complete revolution of the shaft 6 the recess 58 in the valve 54 will be caused to pass over the aperture 56 in the circular projection 55 and lubricant will thus be forced by the pressure 25 in the chamber 40 through said aperture into the chamber 60 and passing down through the duct 57 be discharged into the cup 36, being thrown outward against the wall of said cup by centrifugal force. From 30 this cup it passes through the ducts 37, 38 and 39 to lubricate the eccentrics on the shaft, as previously described. This lubricant then falls into the bottom of the low pressure chamber and maintains a substantially uniform height of lubricant therein, 35 as indicated by "x." The lubricant thus deposited in the low pressure chamber is returned to the high pressure chamber by the action of the compressors in the manner 40 previously described. One of the principal features of the invention is the fact that the body of liquid in the low pressure chamber 9 is always accessible under the force of gravity and the slight pressure in the chamber 45 9, to the stuffing box 14, by means of the apertures 15 in the bearing 13; so that it is impossible for gas in the chamber 9 to escape through the stuffing box 14. Of course, the packing 16 of the stuffing box can be 50 compressed as tightly about the shaft as may be desired by screwing up the cap of the box in the usual way.

Referring to the low pressure chamber 9, it will be seen that the cylinders 18 are inserted from the outside into said chamber and project well toward the center thereof and are surrounded throughout practically their entire length by the cool gas in said chamber which thus tends to prevent the 55 heat of compression from causing a too rapid expansion of the gas that is drawn into the cylinders. This, as is well understood, will increase the efficiency of the apparatus.

60 It will further be seen that the outside

ends of the cylinders or cylinder castings which have been referred to as "heads," are closed by removable heads or covers 25, and as the cylinders themselves are removable the ready assemblage of the parts and 70 equally ready access to all parts of the movable mechanism in or connected with the low pressure chamber is assured.

We should point out that in the reciprocation of the pistons of the compressors not 75 only is the lubricant returned to the high pressure chamber, but in this operation it is also necessarily supplied to and distributed over the interior of the cylinders so as to thoroughly lubricate the pistons and cylinders 80 and the connections of the piston rods with the pistons. The thorough lubrication of all movable parts provided for by our invention is of great importance in high speed reciprocating machines such as our 85 invention contemplates. Not only is the thorough lubrication of the cylinders provided for as described, but as the lubricant in the low pressure chamber is always in contact with the cold gaseous refrigerant, 90 the lubricant is maintained at a relatively low temperature and is an important factor 95 in cooling the cylinders.

Another feature of great importance and, in fact, necessary to the successful operation 100 of a refrigerating machine of the reciprocating type shown, at a very high rate of speed, is the provision of the floating heads at the ends of the cylinders in combination with the inlet ports 19 for the gaseous refrigerant. 105 In other words, the construction is valveless, so to speak, for, while the floating heads act in the nature of valves, they differ from an ordinary valve in the area uncovered relative to the area of compression released. In 110 other words, on the out stroke of the piston when the gas has been compressed to a certain point, the whole end of the cylinder is uncovered and an instant release of the pressure in the cylinder over its entire area is effected. There is no danger, therefore, of building up pressure in the cylinder by rapid successive compressions of the gas due to an inadequate area of expulsion of the gas 115 which would almost certainly result from the use of ordinary valves affording only a relatively small area of expulsion for the gas. These floating heads are equally important in connection with the lubricating feature described for as relatively large 120 quantities of the lubricant will be drawn into the cylinders on each suction stroke, it is of the utmost importance that the free discharge of this lubricant should occur at each compression stroke of the pistons, and this is provided for by the floating heads 125 which, as will be apparent, yield under compression to permit lubricant to be discharged from the entire inner surface of each cylinder.

- Again, as the pistons move inward and uncover the inlet ports, the gas can rapidly enter the cylinder, as the ports are not controlled by valves. The rapid entrance of the gas is facilitated by the relatively large area of inlet afforded by the openings around the cylinder, by the partial vacuum produced on the interior of the cylinder by the movement of the piston and by the pressure in the low pressure chamber which, while not considerable, say about 7 lbs. to the square inch, is sufficient under the conditions named to effect a rapid entrance of the gas into the cylinder.
- 15 In practice the pistons reciprocate at from 1000 to 1200 times per minute. Notwithstanding, due to the dynamic and mechanical balance which the construction provides, the thorough automatic lubrication of all parts subject to movement and friction, and the provision for the rapid ingress of the gas into and its ready and complete expulsion from the cylinders, we have demonstrated in practice that a machine so constructed and having the characteristics enumerated, will operate uniformly, noiselessly, with a practical absence of vibration, and with high efficiency. It should furthermore be observed that owing to the large area made available for the expulsion of the gas and air, the movement of the floating heads need only be very slight, say $\frac{1}{2}$ of an inch or even less, so that notwithstanding the extreme rapidity of the reciprocations of the pistons, the floating heads respond with the necessary rapidity to both the compression and suction impulses set up by the pistons.
- We claim:
- 40 1. A refrigerating machine comprising a casing enclosing a high pressure and a low pressure chamber, the former being superimposed upon the latter, compressors for the refrigerant located in and having intakes communicating directly with the low pressure chamber, said compressors having valved communication with the high pressure chamber, means for conducting evaporated refrigerant into the low pressure chamber, bearings provided in a wall of the low pressure chamber and an opposite partition separating the two chambers, a drive shaft for operating said compressors projecting from the outside into and through said low pressure chamber and mounted toward its ends in said bearings, and means for driving said shaft.
- 45 2. A refrigerating machine comprising a casing enclosing a high pressure and a low pressure chamber, means for conducting evaporated refrigerant into said low pressure chamber, compressors for the refrigerant located in and having intakes communicating directly with the low pressure chamber, said compressors having valved communication with the high pressure chamber, a drive shaft entering said low pressure chamber through its bottom for operating said compressors, means for driving said shaft, and a combined bearing and stuffing box provided for said shaft on the bottom of the low pressure chamber, the stuffing box being accessible to a lubricant maintained in the bottom portion of said low pressure chamber.
- 50 3. A refrigerating machine comprising a casing enclosing a high pressure and a low pressure chamber, means for conducting evaporated refrigerant into said low pressure chamber, compressors for the refrigerant located in and having intakes communicating with the low pressure chamber, said compressors having valved communication with the high pressure chambers, a drive shaft projecting through the bottom of said low pressure chamber into the same for actuating said compressors, a bearing for said shaft provided on the bottom and projecting into the interior of the low pressure chamber, and a stuffing box for the shaft located exteriorly of the chamber, said bearing being provided with apertures for permitting access to said stuffing box of lubricant maintained in the lower part of said low pressure chamber.
- 55 4. A refrigerating machine comprising a casing enclosing a high pressure and a low pressure chamber, each of which chambers contains a body of lubricant, means for conducting evaporated refrigerant into the low pressure chamber, compressors for the refrigerant located in and having intakes communicating with the low pressure chamber, said compressors having valved communication with the high pressure chambers, a drive shaft for actuating the compressors having bearings in corresponding walls of said chamber, the wall of the high pressure chamber affording a passage for lubricant from said chamber to the low pressure chamber to lubricate the compressing mechanism therein, and means for controlling the flow of lubricant from the high pressure chamber through said passage.
- 60 5. A refrigerating machine comprising a casing enclosing a high pressure and a low pressure chamber, each of which chambers contains a body of lubricant, means for conducting evaporated refrigerant into the low pressure chamber, compressors for the refrigerant located in and having intakes communicating with the low pressure chamber, said compressors having valved communication with the high pressure chambers, a drive shaft for actuating the compressors projecting through corresponding walls of said chambers, the wall of the high pressure chamber affording a passage for lubricant from said chamber to the low pressure chamber to lubricate the compressing

mechanism therein, and means operated by the drive shaft for controlling the flow of lubricant from the high pressure chamber through said passage.

5   6. A refrigerating machine comprising a
casing enclosing a high pressure and a low
pressure chamber, each of which chambers
contains a body of lubricant, compressors
for the refrigerant located in the low pres-
10   sure chamber, a drive shaft for actuating the
compressors projecting through correspond-
ing walls of said chambers, the wall of the
high pressure chamber affording a passage
for lubricant from said chamber to the low
15   pressure chamber to lubricate the compress-
ing mechanism therein, and means located in
the high pressure chamber and operated by
the drive shaft to control the flow of lu-
bricant from said chamber through said
20   passage.

20 **7. A refrigerating machine comprising a casing enclosing a high pressure and a low pressure chamber, each of which chambers contains a body of lubricant, means for 25 conducting evaporated refrigerant into the low pressure chamber, compressors for the refrigerant located in and having intakes communicating with the low pressure chamber, said compressors having valved communication with the high pressure chambers, a drive shaft for actuating the compressors having bearings in corresponding walls of 30 said chambers, the wall of the high pressure chamber affording a passage for lubricant 35 from said chamber to the low pressure chamber, means in the latter chamber for distributing lubricant from said passage to the compressing mechanism, and means for controlling the flow of lubricant from the 40 high pressure chamber through said passage.**

40 high pressure chamber through said passage.

45 8. A refrigerating machine comprising a casing enclosing a high pressure and a low pressure chamber, each of which chambers contains a body of lubricant, means for conducting evaporated refrigerant into the low pressure chamber, compressors for the refrigerant located in and having intakes communicating directly with the low pressure chamber, a drive shaft for actuating the compressors having bearings in corresponding walls of said chambers, the wall of the high pressure chamber affording a passage for lubricant from said chamber to the low pressure chamber, means in the latter chamber mounted on the drive shaft for receiving and distributing lubricant from said passage to the compressing mechanism, and means operated by the drive shaft for controlling the flow of lubricant from the high pressure chamber through said passage.

9. A refrigerating machine comprising a casing enclosing a high pressure and a low pressure chamber, each of which chambers contains a body of lubricant, means for con-

ducting evaporated refrigerant into the low pressure chamber, compressors for the refrigerant located in and having intakes communicating directly with the low pressure chamber, said compressors having valved communication with the high pressure chamber, a drive shaft for actuating the compressors projecting through corresponding walls of said chambers, the wall of the high pressure chamber affording a passage for lubricant from said chamber to the low pressure chamber, means in the latter chamber for distributing lubricant from said passage to the compressing mechanism, and means located in the high pressure chamber and operated by the drive shaft to control the flow of lubricant from said chamber through said passage.

10. A refrigerating machine comprising a casing enclosing a high pressure and a low pressure chamber, each of which chambers contains a body of lubricant, means for conducting evaporated refrigerant into the low pressure chamber, compressors for the refrigerant located in and having intakes communicating directly with the low pressure chamber, said compressors having valved communication with the high pressure chamber, a drive shaft for actuating the compressors having bearings in corresponding walls of said chambers, the wall of the high pressure chamber affording a passage for lubricant from said chamber to the low pressure chamber, means in the latter chamber for distributing lubricant from said passage to the compressing mechanism, means for controlling the flow of lubricant from said chamber through said passage, and means including the compressors for returning the lubricant from the low pressure chamber to the high pressure chamber.

11. A refrigerating machine comprising a casing enclosing a high pressure and a low pressure chamber, each of which chambers contains a body of lubricant, means for conducting evaporated refrigerant into the low pressure chamber, compressors for the refrigerant located in and having intakes communicating directly with the low pressure chamber, said compressors having valved communication with the high pressure chamber, a drive shaft for actuating the compressors projecting through corresponding walls of said chambers, the wall of the high pressure chamber affording communication for lubricant from said chamber to the low pressure chamber to lubricate said compressing mechanism, and means operated by the drive shaft to alternately open and close the communication between the two chambers to control the flow of lubricant under pressure in the high pressure chamber through said passage.

12. A refrigerating machine comprising a ¹³⁰

- casing enclosing a high pressure and a low pressure chamber, each of which chambers contains a body of lubricant, means for conducting evaporated refrigerant into the low pressure chamber, compressors for the refrigerant located in and having intakes communicating directly with the low pressure chamber, said compressors having valved communication with the high pressure chamber, means for actuating said compressors, and a plurality of means, including the compressors, actuated in the operation of the machine to controllably supply lubricant from the high pressure chamber to the low pressure chamber, to distribute the lubricant to the compressing mechanism in the latter chamber, and to return surplus lubricant from the low pressure to the high pressure chamber.
13. A refrigerating machine comprising a casing enclosing a high pressure and a low pressure chamber, each of which chambers contains a body of lubricant, means for conducting evaporated refrigerant into the low pressure chamber, compressors for the refrigerant located in and having intakes communicating directly with the low pressure chamber, said compressors having valved communication with the high pressure chamber, a drive shaft projecting through corresponding walls of said chambers, the wall of the high pressure chamber affording a passage for lubricant from said chamber to the low pressure chamber, means mounted on the drive shaft for operating said compressors, means carried by the shaft for receiving and distributing the oil to the compressing mechanism, means operated by the drive shaft for controlling the flow of lubricant from the high pressure chamber through said passage under the pressure of the lubricant in the high pressure chamber, and means, including the compressing mechanism, for returning surplus lubricant from the low pressure to the high pressure chamber, whereby to maintain a substantially constant oil level in said chambers.
14. A refrigerating machine comprising a casing enclosing a high pressure and a low pressure chamber, each of which chambers contains a body of lubricant, means for conducting evaporated refrigerant into the low pressure chamber, compressors for the refrigerant located in and having intakes communicating directly with the low pressure chamber, said compressors having valved communication with the high pressure chamber, a drive shaft projecting through corresponding walls of said chamber, means mounted on the drive shaft for operating said compressors, said means being provided with ducts for the flow of lubricant and the wall of the high pressure chamber affording a passage for lubricant from said chamber to the low pressure chamber, means carried by the shaft for receiving and distributing the oil to the compressing mechanism, means operated by the drive shaft for controlling the flow of lubricant from the high pressure chamber through said passage under the pressure of the lubricant in the high pressure chamber, and means, including the compressing mechanism, for returning surplus lubricant from the low pressure to the high pressure chamber, whereby to maintain a substantially constant oil level in said chambers.
15. A refrigerating machine comprising a casing enclosing a high pressure and a low pressure chamber, means for conducting evaporated refrigerant into the low pressure chamber, compressors for the refrigerant located in and having intakes communicating directly with the low pressure chamber, each of which compressors comprises in turn a cylinder provided with an exterior head affording a chamber having valved communication with the cylinder, pipes affording communication between each of said chambers and the high pressure chamber, a piston in each of said cylinders, a drive shaft extending into the low pressure chamber at right angles to the axes of said cylinders, means on said drive shaft for actuating said pistons, and means for actuating the drive shaft.
16. A refrigerating machine comprising a casing enclosing a high pressure and a low pressure chamber, means for conducting evaporated refrigerant into the low pressure chamber, compressors for the refrigerant located at opposite sides of and having intakes communicating directly with the low pressure chamber, each of which compressors comprises in turn a cylinder projecting into the low pressure chamber and provided with an exterior head affording a chamber having valved communication with the cylinder, pipes affording communication between each of said chambers and the high pressure chamber, a piston in each of said cylinders, a drive shaft extending into the low pressure chamber at right angles to the axes of said cylinders, means on said drive shaft for actuating said pistons, and means for actuating the drive shaft.
17. A refrigerating machine comprising a casing enclosing a high pressure and a low pressure chamber, each of which chambers contains a body of lubricant, means for conducting evaporated refrigerant into the low pressure chamber, compressors for the refrigerant located in the low pressure chamber, and having valved communication with the high pressure chamber, means for actuating said compressors, a condenser for the compressed refrigerant in the high pressure chamber, the wall of the high pressure chamber affording a passage for lubricant from said chamber to the low pressure chamber to lubricate the compressing mechanism in the

- latter, means, including one of said compressors, for returning excess lubricant from the low pressure to the high pressure chamber, and means for withdrawing for use the 5 condensed refrigerant superimposed upon the body of lubricant in the high pressure chamber.
18. A refrigerating machine comprising a casing enclosing a high pressure and a low 10 pressure chamber, each of which chambers contains a body of lubricant, means for conducting evaporated refrigerant into the low pressure chamber, compressors for the refrigerant located in the low pressure chamber, 15 and having valved communication with the high pressure chamber, means for actuating said compressors, a condenser for the refrigerant, located in the high pressure chamber, whereby a body of condensed refrigerant 20 will be constantly superimposed upon the body of lubricant in the high pressure chamber, means for withdrawing condensed refrigerant from above the level of the lubricant in the high pressure chamber, means for 25 simultaneously withdrawing lubricant from below the level of the lubricant in the bottom of the high pressure chamber for lubricating the compressing mechanism in the low pressure chamber, and means for returning 30 excess lubricant from the low pressure to the high pressure chamber.
19. A refrigerating machine comprising a casing enclosing a high pressure and a low pressure chamber, the former being superimposed upon the latter and each of said 35 chambers containing a body of lubricant, means for conducting evaporated refrigerant into the low pressure chamber, a bearing provided in the bottom of each of said chambers 40 and surrounded and lubricated by the lubricant thereof, compressors for the refrigerant located in and having intakes communicating directly with said low pressure chamber, said compressors having valved 45 communication with the high pressure chamber, and a drive shaft for actuating said compressors extending through said low pressure chamber and mounted near its opposite ends in the said bearings.
50. 20. A refrigerating machine comprising a casing enclosing a high pressure and a low pressure chamber, each of which chambers contains a body of lubricant, means for conducting evaporated refrigerant into the low pressure chamber, compressors for the refrigerant located in and having intakes communicating directly with the low pressure chamber, said compressors having valved 55 communication with the high pressure chamber, a drive shaft for actuating the compressors projecting through corresponding walls of said chambers, the wall of the high pressure chamber affording a passage for lubricant from said chamber to the low pressure 60 chamber, means mounted on the drive shaft for actuating the compressors, said means being located beneath the discharge end of said passage for receiving lubricant therefrom and provided with means for conveying the lubricant to the moving parts 70 of the actuating and compressing mechanism, whereby the lubricant while flowing from the high to the low pressure chamber will be caused to lubricate all of said moving parts, and means for automatically controlling the discharge of lubricant from the high pressure chamber through said passage under the pressure in said chamber.
21. A refrigerating machine comprising a 80 casing enclosing a high pressure and a low pressure chamber, means for conducting evaporated refrigerant into the low pressure chamber, compressor cylinders for the refrigerant located at diametrically opposite sides of and within the low pressure chamber, and each of which cylinders is provided with a piston, a drive shaft extending into the low pressure chamber at right angles to the axes of said cylinders, means on said shaft for actuating said pistons synchronously, alternately in opposite directions, inlet ports in said cylinders in free communication with the low pressure chamber, floating heads on the compression ends of the cylinders movable under pressure to uncover the entire area of the cylinders, and means for conducting gas expelled from the cylinders to the high pressure chamber.
22. A refrigerating machine comprising a 90 casing enclosing a high pressure and a low pressure chamber, the latter containing a body of lubricant, means for conducting evaporated refrigerant into the low pressure chamber, compressors for the refrigerant located in and having intakes communicating directly with the low pressure chamber, said compressors having valved communication with the high pressure chamber, means for actuating the compressors, pipes communicating with said compressors and having a common connection provided with an opening located adjacent the surface of said body of lubricant, whereby, in the operation 100 of the compressors, lubricant will be simultaneously drawn into each compressor, and floating heads on each cylinder adapted to yield under the compressive action of the pistons to permit the free discharge of oil 110 from the cylinders.
23. A refrigerating machine comprising a 115 casing enclosing a high pressure and a low pressure chamber, the latter of which contains a body of lubricant, means for conducting evaporated refrigerant into the low pressure chamber, compressors for the refrigerant located in the low pressure chamber, each of said compressors including cylinders provided with inlet ports freely communicating 125 with the interior of said low pressure chamber,

ber, said compressors having valved communication with the high pressure chamber, means for actuating the compressors, pipes communicating with the interior of said cylinders in advance of said inlet ports and having a common inlet located near the surface of said body of lubricant, and a floating head on each of said cylinders adapted to yield under the compressive action of the 10 pistons to permit the free discharge of the lubricant from the cylinders.

24. A refrigerating machine comprising a casing enclosing a high pressure and a low pressure chamber, each of which chambers 15 contains a body of lubricant, means for conducting evaporated refrigerant into the low pressure chamber, compressors for the refrigerant located in and having intakes communicating directly with the low pressure 20 chamber, said compressors having valved communication with the high pressure chamber, a drive shaft for actuating the compress-

sors having bearings in corresponding walls of said chambers, the wall of the high pressure chamber affording a passage for lubricant from said chamber to the low pressure chamber, means for controlling the flow of lubricant through said passage, pipes communicating with said compressors and having a common inlet located near the surface 30 of the body of lubricant in the low pressure chamber, floating heads for each cylinder adapted to yield under compressive action, whereby, in the operation of the compressors lubricant will be simultaneously drawn into 35 each compressor and freely discharged therefrom, and means for conducting the lubricant discharged from the compressors to the high pressure chamber.

In testimony whereof, we have hereunto 40 set our hands.

JOHN E. MITCHELL.
WALTER G. E. ROLAFF.
